CONTINUOUS TUBE ROLLING MILL

Bryant Bannister, Mount Lebanon, Pa., assignor
to National Tube Company, a corporation of
New Jersey

Application September 29, 1942, Serial No. 460,151

8 Claims.

(Cl. 80—11)

This invention relates to continuous tube rolling mills and particularly to an improved means for and method of determining the stress condition of the tubing between the roll stands of the mill as it passes therethrough.

As is well known, a continuous tube rolling mill comprises a series of roll stands arranged in tandem with the rolls of each stand being grooved and with each stand being individually driven. The rolls of the stands compress and displace the metal of a pierced billet on a cylindrical mandrel arranged within the billet as the billet which is adapted to be formed into tubing passes continuously through the consecutively arranged roll stands of the mill. This type of mill corresponds to the conventional multiple stand mills for rolling flat sheets or plates from heated slabs of metal. In both types of mills, under ideal conditions, the speed of each roll stand should be such that it tends to take metal from the preceding stand at substantially the same rate that the metal is delivered from such stand. It will be seen that if the speed of the rolls of the respective stands is too great to meet this condition that portion of the metal between the stands while being rolled tends to be stretched and if the speed of the rolls is too low the metal is subjected to compression, or looping occurs between the stands.

In a sheet or plate mill it is comparatively simple to adjust properly the roll speeds for there is nothing between the stands except the sheet or workpiece and various means have been suggested and used for equalizing the speed of the rolls in such mills. However, in a tube rolling mill, in addition to the billet or workpiece between each of the stands, there is arranged within the billet a rigid mandrel for supporting the metal during the working thereof by the rolls of the stands, a fact well known to those skilled in the art of tube rolling. In a tube mill it will be seen that the mandrel will travel at only one speed through the roll stands at any one time, which speed is faster than the peripheral speed of the rolls in the first stands of the mill and slower in the later stands. Also, the speed of the mandrel changes from the time it enters the mill until the time it leaves and it is desirable that the metal of the billet or tubing around the mandrel between adjacent roll stands be neither in tension nor compression. It will be understood that if such ideal conditions are maintained, slippage, wear on the rolls and loss of power are reduced to a minimum.

It will be seen then that if it can be ascertained whether the billet or workpiece passing through the stands or mill is being delivered from any par-

ticular stand not fast enough or too fast, the speed of the roll stand to which it is being delivered may be regulated so that stresses are eliminated from that portion of the billet or workpiece disposed between the stands. It is to such means and method of determining whether the workpiece between the stands is under stress, i. e. compression or tension, that the present invention relates.

10 Accordingly, it is the general object of the present invention to provide in a continuous tube rolling mill an improved means for and method of determining the stress condition of that portion of a tube or workpiece disposed between the succeeding stands of the mill.

It is another object of the invention to provide an improved means for and method of indicating in a continuous tube rolling mill whether that portion of the workpiece between the respective 20 stands of the mill is under tension or compression.

It is a further object of this invention to provide an improved method of operating a continuous tube rolling mill which comprises determining whether that portion of the billet or workpiece between the succeeding stands of the mill is under either compression or tension, and then regulating the speeds of the rolls of the respective stands so that the workpiece is not subject to either tension or compression.

30 Various other objects and advantages of this invention will become more apparent during the course of the following specification and will be particularly pointed out in the appended claims.

In the accompanying drawings there is shown 35 for the purpose of illustration an embodiment which my invention may assume in practice.

In the drawings:

Figure 1 is a plan view, partly in section, of any two roll stands of a continuous tube rolling mill 40 showing the positions the workpiece and mandrel assume while passing therethrough and with which the improved indicating means of my invention is shown incorporated;

Figure 1A is a sectional view taken on line 1A—45 1A of Figure 1;

Figure 1B is a sectional view taken on line 1B—1B of Figure 1;

Figure 2 is a sectional view taken on line II—II of Figure 1;

50 Figure 3 is a view taken at right angles to the view shown in Figure 1 showing only one roll stand and the position of my improved indicating means relative to the rolls thereof, with the workpiece shown therein being under normal stress;

55 Figure 4 is a view similar to Figure 3 showing

a workpiece disposed between the rolls of the stand which is under compression; and

Figure 5 is a view also similar to Figure 3 showing the workpiece under tension.

Figure 6 is a view taken similarly to Figure 2 but showing a modification having a speed control for the motor of the successive roll stand.

Referring more particularly to the drawings, there are shown in Figure 1 for the purpose of illustration two roll stands 2 and 3, each having opposed grooved rolls 4. It will be understood that these two roll stands as shown may be any two stands of a conventional continuous tube rolling mill in which the roll stands are arranged in tandem. There is shown disposed in and passing through the roll stands 2 and 3 a workpiece or billet B having a cylindrical mandrel M arranged therewithin, both of which pass between the stands in a well-known manner. In order to determine the stress conditions of the workpiece between the stands such as the two shown in the present instance, it will be understood that it is necessary to derive such information from the workpiece or billet itself while the same passes between the stands of the mill. It will be noted that the workpiece or billet B has a decided oval cross section while in and immediately after leaving stand 2 as shown in Figure 1A of the drawings and that it has a similar oval cross section while in and immediately after leaving stand 3 but the long and short axes of the oval cross section of the workpiece or billet are displaced 90° in stand 3 from their position in stand 2 as shown in Figure 1B of the drawings. Since there is no external force acting upon the workpiece or billet between stands 2 and 3 there is no influence to alter the shape or position of the oval cross section of the billet immediately after leaving stand 2 until it reaches a point near stand 3 where the long and short axes necessarily reverse their positions due to the fact that the axes of the rolls 4 in stand 3 are positioned substantially perpendicular to the axes of the rolls 4 in stand 2. Thus, it will be seen that from the axial length and cross section of this transition zone of the billet between the stands, stands 2 and 3 in the present instance, the stresses in the workpiece or billet can be ascertained. For example, if the pivotal speed of the rolls 4 in stand 3 is greater than that of the entering workpiece or billet, tension will result in that portion of the workpiece between stands 2 and 3 and the length of the transition zone will be increased with the vertical axis becoming shorter while the horizontal axis will become greater. It will be understood that the basis of this phenomenon is that the shortest distance between two points is a straight line. Such a result applies in the present instance for the reason that the rolls in stand 3 grip the workpiece at the top and bottom thereof as shown, compressing it against the mandrel within the workpiece, thereby tending to pull more metal into the pass between the rolls of the stand 3 than is being supplied by stand 2 thereby tending to straighten out the hump or projecting portion of the workpiece occurring immediately ahead of stand 3. The flare in the grooved rolls of stand 3 permits the horizontal axis of the workpiece to increase as the vertical axis decreases since the perimeter of the oval cross section remains unchanged. Conversely, it will be seen that if the peripheral speed of the rolls in stand 3 is less than the rate of speed or advance of the workpiece thereto the vertical axis will be maintained substantially constant until the workpiece reaches a point closer to stand

3. Such action will shorten the transition zone and cause the horizontal axis of the oval section also to remain constant until it reaches a point closer to stand 3.

5 According to the present invention it is proposed to utilize the above-outlined phenomenon to ascertain whether that portion of the workpiece or billet B between any two stands is under stress, namely tension or compression, and then to regulate the speed of the rolls of the respective stands so as to eliminate the stress condition so that the workpiece or billet is subjected to neither compression nor tension. In order to carry out the teachings of the present invention there is arranged at a point immediately in front of the rolls 4 of the advanced stand, or stand 3 as shown in the present instance, means for contacting the workpiece or billet as it passes between the stands in order to ascertain whether or not that portion of the workpiece or billet between the stands is under compression or tension. It will be understood that any suitable contact means may be used for indicating the stress condition of the workpiece between the stands. In the present instance there is shown a means which is most suitable for ascertaining this stress condition. As shown in Figures 1 and 2 of the drawings there is positioned adjacent the advanced stand, or stand 3 as shown, a supporting means or bracket 5 having a threaded aperture 6 arranged therethrough. There is arranged in the threaded aperture of the bracket 5 an exteriorly threaded collar or sleeve member 7. There is slidably arranged through the collar 7, a rod 8 for reciprocable movement.

10 15 20 25 30 35 40 45 50 55 60 65 70 75 On the outer end of the rod 8 there is mounted a forked member 9 between the legs of which there is rotatably mounted a roller 10 on pin 12. Around the slidable rod 8 and between the forked member 9 and the sleeve 7 there is disposed preferably a coil spring 13. The roller 10 is disposed preferably at a point in the crotch between the rolls 4 of the advanced stand, or stand 3 as shown in Figure 1 of the drawings. It will be understood that the roller 10 is adapted to contact the outer side wall of the workpiece or billet at all times while the same is passing through the mill and functions in a manner hereinafter to be described.

Adjacent the other end of the shaft or rod 8 there is positioned a pointer or indicating means 14 which is pivotally supported intermediate its length at 15. One end of the pointer or indicating means 14 is pivotally connected to the outer end of the shaft or rod 8 at 16. There is securely carried by the shaft or rod 8 at a point beyond the sleeve 7, a collar member 17 which is adapted to limit the inner movement of the rod or shaft 8. Adjacent the outer end of the pointer or indicating means 14 there is arranged preferably a segmental dial member 18 having calibrations 19 arranged thereon with which the pointer or indicator 14 is adapted to cooperate so as to indicate the stress conditions of the workpiece or billet.

As shown in Figure 6, the contacting device may be connected to a variable speed motor which drives the rolls of the successive stand adjacent the contactor. In the arrangement shown, the arm 14a is in contact with a resistance 20 and is connected in series therewith to a source of power and field 21 of the roll motor. Armature 22 of the roll motor is likewise connected to a suitable source of power. Thus it is seen that as the roller moves inwardly or outwardly, more or less resistance will be placed in the circuit to slow or speed up the roll motor. Thus the speed of the motor

will be automatically varied to reduce tension or compression in the workpiece.

The apparatus of my invention functions in the following manner. It will be understood that the roller 10 contacts the workpiece or billet at the transition zone between the roll stands at all times while the same is passing through the mill. From what has been hereinbefore stated when the workpiece goes into tension from a neutral condition of stress between any two roll stands, it will be seen that the contact member or roller 10 will move outwardly as the horizontal axis of the workpiece increases and inwardly as the horizontal axis decreases and as the workpiece is subjected to compression stresses. Between these two extremes it will be understood that the workpiece is under practically no stress. Thus it will be seen that when that portion of the workpiece or billet between stands 2 and 3 is under tension the roller 10 together with the shaft or rod 3 upon which it is mounted will move outwardly and the pointer or indicating means will move about its pivotal connection at 15 and indicate on the calibrations 19 of the dial 18 that the workpiece or billet is under tension as shown in Figure 5 of the drawings. If that portion of the workpiece between stands 2 and 3 is under compression the roller 10 together with the shaft or rod 8 will move inwardly thereby moving the indicating means or pointer 14 about its pivotal connection so as to indicate on the dial 18 that the workpiece is under compression as shown in Figure 4 of the drawings. If the workpiece or billet is under neither compression nor tension the roller together with the pointer or indicating means will not be moved and the pointer will indicate a neutral or normal position as shown in Figure 3 of the drawings. After it has been determined whether or not the workpiece between the roll stands is under compression or tension, the speed of the respective rolls of the stands is increased or decreased so as to satisfy the condition until the indicating means or pointer 14 will assume a normal condition as shown in Figure 3 of the drawings which, of course, is the ideal operating condition of the mill. It will be understood that a device or mechanism similar to that shown in the drawings is mounted immediately ahead of each roll stand of the mill excepting the first stand. It is obvious that the contacting member or roller 10 can be actuated by the metal of the workpiece or billet in the plane of either the long or short axis of the transition zone, whichever is desired. In the arrangement shown in Figure 6 the contacting devices are interconnected with the roll motors so that the roll speeds are automatically regulated.

As a result of my invention it will be seen that there is provided not only a simple and inexpensive means for determining whether the workpiece or billet between the stands is under compression or tension but at the same time means which is efficient and effective in its operation and use. It will be seen that by the practice of the present invention the speed of the rolls of the respective stands can be accurately maintained so that the metal is supplied to the respective stands at the correct speed thereby providing a finished tubing which has proper dimensions and improved qualities.

While I have shown and described one specific embodiment of my invention, it will be understood that this embodiment is merely for the purpose of illustration and description and that various other forms may be devised within the

scope of my invention, as defined in the appended claims.

I claim:

1. In a continuous tube rolling mill having a plurality of spaced apart roll stands, a roller arranged between at least some of the roll stands which contacts the outer side wall of the tubing as it passes continuously therethrough, said roller having the axis thereof arranged substantially perpendicular to the axis of the tubing, movable means upon which said roller is rotatably mounted, said movable means adapted to move diametrically of the tubing and being responsive to the lateral movement of the roller together with the side walls of the tubing, and means responsive to the movement of said movable means together with said roller for indicating whether the portion of the tubing between the respective stands is under tension or compression.
2. In a continuous tube rolling mill having a plurality of spaced apart roll stands, a roller arranged between at least some of the roll stands which contacts the outer side wall of the tubing as it passes continuously therethrough, said roller having the axis thereof arranged substantially perpendicular to the axis of the tubing, movable means upon which said roller is rotatably mounted, said means adapted to move diametrically of the tubing and being responsive to the lateral movement of the roller together with the side walls of the tubing, a pointer which is mounted for pivotal movement, said movable means connected to said pointer which it is adapted to actuate, and means with which said pointer cooperates to indicate whether the portion of the tubing between the respective stands is under tension or compression.
3. In combination with a continuous tube rolling mill having a plurality of spaced apart roll stands and a mandrel which is adapted to be disposed within the tubing, means arranged between at least two of the roll stands adjacent the transition zone for contacting the outer side walls of the tubing as the same together with the mandrel passes continuously therewith which is responsive to the variations in diameter of the tubing at the transition zone between the respective roll stands so as to determine whether that portion of the tubing between the roll stands is under tension or compression, said transition zone being that point between the roll stands at which the axis of the oval cross-section of the tubing changes from one plane to another.
4. In a continuous tube rolling mill having a plurality of spaced apart roll stands wherein a tubular workpiece is rolled on a mandrel bar and an oval shape imparted thereto with the axis of ovality changed by successive stands, means responsive to variations in said ovality arranged adjacent the inlet side of a successive stand for determining the amount of reduction of such ovality by such stand at a spaced point in advance thereof to thereby determine whether the workpiece is under tension or compression as it enters such stand, and means connected thereto to vary the speed of the rolls thereof to control the tension or compression in the workpiece as it enters such stand.
5. In a continuous tube rolling mill having a plurality of spaced apart roll stands wherein a tubular workpiece is rolled on a mandrel bar and an oval shape imparted thereto with the axis of ovality changed by successive stands, means responsive to variations in said ovality arranged adjacent the inlet side of a successive stand for

determining the amount of reduction of such ovality by such stand at a spaced point in advance thereof, and means connected thereto to indicate whether the workpiece is under tension or compression as it enters such stand.

6. In a continuous tube rolling mill having a plurality of spaced apart roll stands wherein a tubular workpiece is rolled on a mandrel bar and an oval shape imparted thereto with the axis of ovality changed by successive stands, means engaging an oval portion of the tube wall adjacent the inlet side of a successive stand for determining the amount of reduction of such ovality by such stand at a spaced point in advance thereof to thereby determine whether the workpiece is under tension or compression as it enters such stand, and means connected thereto to vary the speed of the rolls thereof to control the tension or compression in the workpiece as it enters such stand.

7. In a continuous tube rolling mill having a plurality of spaced apart roll stands wherein a tubular workpiece is rolled on a mandrel bar

and an oval shape imparted thereto with the axis of ovality changed by successive stands, means engaging an oval portion of the tube wall adjacent the inlet side of a successive stand for determining the amount of reduction of such ovality by such stand at a spaced point in advance thereof, and means connected thereto to indicate whether the workpiece is under tension or compression as it enters such stand.

8. In the art of continuously rolling tubing in a continuous tube rolling mill wherein a tubular workpiece is rolled on a mandrel which moves therewith in a succession of roll stands wherein an oval shape is imparted thereto with the axis of ovality of the tube changed by successive stands, the steps of determining the amount of such ovality at a spaced point in advance of a successive stand to determine whether the workpiece is under tension or compression as it enters such stand and varying the speed of the rolls of such stand so as to control the tension or compression therein as it enters such roll stand.

BRYANT BANNISTER.
